PAPER TOWEL DISPENSER

John P. Hummel, Hopewell, Va.

Application September 26, 1932
Serial No. 634,842

2 Claims. (Cl. 206—57)

This invention relates to improvements in paper towel dispensers.

One of the objects of the present invention is to provide a cardboard or fiberboard carton or package for a pack of paper towels which will not only serve as the original package for the towels for shipment and sales purposes, but which will also function as a dispenser for the towels as they are required for use.

10 A further object of the invention is to provide a paper towel package and dispenser wherein access to the housed towels is gained through the outward flexing of a pair of flaps, and the individual towels being withdrawable from the dispenser through the opening controlled by the flaps in alternate directions, and in a manner so that upon the withdrawal of a sheet, the succeeding sheet is brought to an exposed position to facilitate its withdrawal.

20 A further object of the invention is to provide a container of the class described formed to position the partially withdrawn sheets to facilitate grasping them preparatory to their complete withdrawal, and to permit the opening to the 25 container being sufficiently protected and shielded at all times, the container being so inexpensive, however, as to permit its being destroyed when all the sheets have been used up.

A further object of the invention is to provide 30 a dispensing container for paper towels having a reenforced wall portion formed with slots therethrough whereby the container slots may be engaged with lugs or screws for mounting on a wall or support, and by reason of the formation of 35 the slots in a reenforced portion of the container, likelihood of the slots being torn or distorted during the normal use of the container, is minimized.

40 A further object of the invention is to provide a dispensing carton for toweling formed and folded from a one-piece blank of cardboard, fiber-board, or the like.

A further object of the invention is to provide 45 a paper towel dispenser which is of very simple construction, is strong and durable, is neat and attractive, and is well adapted for the purposes set forth.

With the above and other objects in view, the 50 invention consists of the improved paper towel dispenser, and its parts and combinations as set forth in the claims, and all equivalents thereof.

In the accompanying drawing in which the same reference characters indicate the same 55 parts in all of the views:

Fig. 1 is a plan view of the blank from which the improved dispensing carton is folded;

Fig. 2 is a front view of the dispensing carton on a larger scale, part being broken away and in section to show constructional details;

60

Fig. 3 is an enlarged vertical sectional view taken on line 3—3 of Fig. 2;

Fig. 4 is an enlarged detail sectional view taken on line 4—4 of Fig. 2;

65

Fig. 5 is a diagrammatic view of the arrangement of the individual paper towels in the relationship in which they are disposed within the container;

Fig. 6 is an end view of the carton embodying an alternative arrangement of the carton end flap means; and

70

Fig. 7 is a sectional view taken on line 7—7 of Fig. 6.

Referring now more particularly to Fig. 1, it will be observed that the blank 8 from which the improved dispensing carton is fashioned, is of one-piece and is generally of rectangular form. Said one-piece sheet is composed of cardboard, fiber-board, or a similar inexpensive flexible material. The blank 8 includes a rear wall portion 9, a bottom portion 10, a front portion 11, a top 12, and a top rear reenforcing flap 13, all separated from one another by longitudinal scored or fold lines 14, 15, 16 and 17 respectively. Foldably attached to each end of the rear 9 are inner end flaps 18, and similar flaps 19, adapted to overlie the flaps 18, are foldably attached to the ends of the front 11. Top and bottom end flaps 20 and 21 are foldably joined to the respective ends of the top 12 and bottom 10. The flaps 18, 21, 19 and 20 are separated from one another by slits 22.

The front portion 11 is formed with a pair of spaced apart, longitudinal scored lines 23 and 24 which are spaced from and parallel with the fold lines 15 and 16 respectively. Between the scored lines 23 and 24, there is a longitudinal slit 25, and transverse slits 26 join the ends of the scored lines 23 and 24. By this arrangement of scored lines and slits on the front 11 of the container, a pair of cooperating outwardly movable or flexing closure and guide flaps 27 and 28 are defined, which, in the ultimate disposition of the container, control access to its interior.

When the blank 8 is folded to form the dispensing carton, the bottom 10 is folded at right angles to the rear portion 9, and the front 11 is folded at right angles to the bottom. Likewise, the top 12 is folded at right angles to the front so as to meet the free edge of the rear 12, and the

100

105

110

top rear reenforcing flap 13 is folded so as to be overlapped by the upper portion of the rear, and said overlapped portions are then glued or otherwise caused to adhere. It will be noted that the 5 upper edge portion of the rear has a pair of securing screw openings 29 therethrough, and similar openings 30 in the flap 13 register therewith. Due to the double thickness of stock caused by the underlapping flap 13 with the openings 10 through both thicknesses, said openings are reinforced and will not readily tear out.

When the carton is folded as above, it can, if desired, be flattened out for storage or transportation. When a carton is to be filled it is, 15 however, in the form previously mentioned, with the ends open. The improved dispensing carton is intended to hold a stack or pile of individual kraft paper towels and the stack of towels, indicated generally by the numeral 31, is packed into 20 the carton through one end, and occupies the interior of the carton, as in Fig. 3. The carton ends may then be closed and secured, and this is accomplished by folding in the flaps 20 and 21, after which the flaps 18 are folded in, and the 25 flaps 19 are last folded against the flaps 18 and are glued or otherwise secured thereto. The complete, filled dispensing carton is then ready for sale and use, and inasmuch as the front flaps 27 and 28 have not at that stage been bent or flexed 30 outwardly, the front of the carton is closed and protected. While it has been mentioned that the front flaps 27 and 28 are defined by slits 24 and 26, weakened or perforated lines may be formed in lieu thereof which may be broken through by 35 the user, so that until said lines are broken through, the carton is completely closed and sealed.

The arrangement of the end flaps has been described, but it is contemplated that the alternative arrangement disclosed in Figs. 6 and 7 40 may be used. In this form the flaps 18 of the principal form are omitted, and the outer flaps 19 are provided at their outer edges with right angular tuck-in flaps 32 which engage inner surfaces of the carton portions 13 adjacent side 45 edge portions of the flaps 20 and 21.

The manner in which the individual towel sheets are arranged in a stack is illustrated diagrammatically in Fig. 5. Each sheet 33 is 50 folded medially and, except for the first and last sheets, one half of each of the adjacent sheets is engaged within the fold of a sheet thereadjacent with the result that the free ends of the sheets are directed in alternate directions.

55 When the dispensing carton reaches the ultimate user it is mounted on a wall or vertical support in the position shown in Figs. 2 and 3 with the front 11 outermost. The support must be provided with a pair of spaced screws or 60 pegs which are engaged in the recesses 29-30,

and in this manner the carton is properly hung. When access to the towels within the container is desired the front flaps 27 and 28 are flexed or bent outwardly, as in Fig. 3, and then the outermost sheet is pulled out of the opening exposed 80 by the flaps 27 and 28. By the act of removing this sheet the free edge of the next sheet, directed in the opposite direction, is pulled partially through the opening so as to be easily grasped when required. During the act of removing the individual sheets, they are pulled against edge of surface portions of the flaps 27 and 28 which act as guides.

From the foregoing it will be seen that the improved dispensing carton is formed in a simple 90 manner from a one-piece blank which, before being filled, can be in a knock-down condition for convenience in storage. When filled, the carton serves originally as a package for the towels, and then is used by the purchaser as a convenient dispensing container which can be discarded when the contents are exhausted. The front flaps when in normal position close and protect the interior of the carton, while when they are bent outwardly they serve as guides facilitating 100 the removal of the towels. The entire carton is strong, is easily mounted on a support, and the support engaging portion is reenforced. Also, the improved paper towel dispenser is of simple 105 and novel construction, and is well adapted for the purposes set forth.

What is claimed as the invention is:

1. A dispensing carton, comprising a one-piece blank foldable into a geometric form to provide a container of rectangular form in cross section, the front wall of the container having a flap underlapping an edge portion of the rear wall and secured thereto to provide a reenforced area, there being openings formed in said reenforced area, the front wall having a dispensing opening 115 therein extending longitudinally of said wall, and a pair of flexible flaps controlling said dispensing opening.

2. A dispensing carton, comprising a one-piece blank foldable into a geometric form to provide 120 a container of rectangular form in cross section, a wall of the container having a flap underlapping an edge portion of another wall and secured thereto to provide a reinforced area, there being openings formed in said reinforced area, the 125 front face of the container having formed thereon a pair of spaced fold lines extending the length of said face and transverse weakened lines at the ends of said face and joining the ends of the fold lines, and a longitudinal weakened line intermediate the fold lines, all of said weakened lines being severable to define a pair of closure flaps foldable outwardly on said fold lines to afford access to the interior of the carton.
